UNITED STATES PATENT OFFICE.

CARTER A. WILLIS AND REUBEN M. WILLIS, OF CHANUTE, KANSAS.

SEPARATOR.

1,274,486.

Specification of Letters Patent.

Patented Aug. 6, 1918.

Application filed March 29, 1917. Serial No. 158,362.

To all whom it may concern:

Be it known that we, CARTER A. WILLIS and REUBEN M. WILLIS, citizens of the United States, residing at Chanute, in the 5 county of Neosho and State of Kansas, have invented certain new and useful Improvements in Separators, of which the following is a specification.

This invention relates generally to separators, and particularly to apparatus for 10 recovering gases.

The primary object of the invention is to provide an improved mechanism for treating exhaust or waste oils and water, and 15 which recovers from such waste the gases which are ordinarily lost. A further object of the invention is to provide an apparatus of this character which is automatic in operation, thereby requiring no attention while 20 performing its functions, and which is simple and inexpensive in construction and maintenance.

With these objects in view, together with others which will appear as the description 25 proceeds, the invention resides in the novel construction, combination, and arrangement of parts, all as will be described more fully hereinafter, illustrated in the drawings, and particularly pointed out in the claims.

30 In the drawings:—

Figure 1 is a vertical longitudinal sectional view taken through the housing for the separating apparatus, and illustrating in elevation a separating device embodying 35 the invention;

Fig. 2 is a horizontal fragmentary section taken through the casing and illustrating in top plan the separating apparatus;

Fig. 3 is a view of one end of the casing 40 and apparatus;

Fig. 4 is a sectional view taken on line 4—4 of Fig. 1;

Fig. 5 is an enlarged sectional view taken 45 through one of the pipe joints used in connection with the apparatus; and

Fig. 6 is a sectional view taken on line 6—6 of Fig. 5.

The invention comprehends generally the 50 employment of a separator tank or compartment, into which the exhaust oils and water are discharged, and which operates in such manner as to permit of the gases carried by the discharge matter to escape, and the oils or water flow from the separator 55 free from gases. The invention further comprehends a tank or compartment of this

character which is arranged so as to automatically compensate for the difference in the volume of waste matter delivered thereto, whereby danger of overflow or choking 60 of the tank is obviated. The apparatus illustrated in the drawings and detailed hereafter is the preferred means for attaining the various ends.

The separator tank is indicated at 10, and 65 in the present instance is shown as being elongated and of cylindrical shape. Communicating with this tank at one end are pipes 11 and 12, the former of which is the intake or feed pipe, and the latter is the 70 duct for leading the recovered gases from the tank. An exhaust pipe 13 is located at that end of the pipe opposite to the connection of the pipes 11 and 12, and communicates with the said tank at the lowest point 75 therein. The exhaust or drain pipe 13 is equipped with a valve 14, so that the flow of water and oil from the tank may be controlled. This tank is preferably disposed 80 at an angle, with its intake end elevated and is capable of moving vertically. A spring 15 supports the tank intermediate the ends thereof, and the said tank, to permit 85 of vertical oscillation thereof, is pivoted at its intake end. As fluid flows into the tank through the pipe 11, the increased weight of the tank will cause the latter to move downwardly upon its pivot and against the tension of the spring 15. As the contents of the tank is exhausted, however, the spring 15 90 restores the tank to its initial position.

The valve 14 is of that type wherein outward movement of the stem 16 opens the same to permit of the contents of the tank escaping therefrom, and is adapted to be 95 actuated by the vertical oscillations of the tank. To this end, a bracket 17 is secured to the valve casing, and vertical arms 18 project upwardly therefrom upon each side of the valve stem. Pivoted at one end to the 100 upper extremity of each of the arms or posts 18 is a lever 19. These levers are, in the present instance, relatively long, and cross each other in the manner illustrated in Fig. 3 of the drawings. A pivot pin 20 105 connects the levers at their point of crossing, and also extends through the valve stem 16. The free ends of the levers 19 are disposed between stops 21 and 22, arranged in spaced 110 relation and in vertical alinement upon each side of the valve. The stops in this form of the invention are illustrated as being

formed of strap metal, shaped to loosely inclose the extremities of the levers.

When the tank is empty, the same will be supported by the spring 15, and the valve 14 will be closed. This valve is forced into closed position by the engagement of the levers 19 with the uppermost stops 21. When matter is introduced to the tank in sufficient quantity, the weight thereof will 10 force the drain end of the tank downwardly, and when the tank has reached a predetermined position, the levers 19 will engage the lower stops 22, whereupon further lowering of the tank will cause the stem 16 of the 15 valve to move upwardly. This operation obviously opens the valve, and the liquid contents thereof can flow through the drain 13. When the weight of the tank contents has been sufficiently reduced or dissipated, 20 the spring 15 will restore the same to initial or raised position, whereupon contact of the free ends of the levers 19 with the upper stops 21 will close the valve 14. It will be understood, of course, that the strength of 25 the spring 15 may be varied as required.

The intake and gas escape pipes 11 and 12 project outwardly from the upper end of the tank, and are then disposed in opposite directions and in axial alinement, as shown 30 in Figs. 1 and 2. The outwardly disposed ends of these pipes are adapted to pivotally support the tank, and the swivel couplings for said pipes with the main feed and exhaust pipes will now be described. The ext- 35 remities of each of the angularly disposed portions of the pipes 11 and 12 are provided with collars or flanges 25, upon each side of which gaskets or washers 26 are positioned. A sliding sleeve 27 incloses the gaskets and 40 flange of each of said pipes, and these sleeves are capable of rotating on their respective pipe ends. Each sleeve is internally threaded on its outer end as shown in Fig. 5, and is coupled by means of such threads to a head 45 28 affixed to the end of the adjacent main feed or exhaust pipe 29 as the case may be. From this construction, it is apparent that the angularly disposed ends of the pipes 11 and 12 are capable of freely rotating in the 50 couplings, and the coupling of each pipe is so made as to preclude the possibility of leakage. The main feed and gas exhaust pipes are rigidly supported upon a suitable frame 30, this frame affording a suitable 55 support for a casing 31 inclosing the tank and its mechanism.

It will be observed that the spring 15 is attached at one end to the frame 30, and tends to pull the free end of the tank upwardly. In the present instance, a pair of 60 such springs are employed, one upon each side of the tank, and the said springs at their lower ends connect with the opposite extremities of the supporting yoke 32 en- 65 gaging the lower surface of the tank.

In addition to the yieldable supporting springs 15, there is provided a supporting apparatus for the tank, and may be used in conjunction with the springs 15, or independently thereof. This supporting means 70 includes a yoke lever 35, upon the bight portion of which a roller 36 is rotatably mounted. Trunnions 37 project outwardly from the bight portion of the lever, and are mounted in suitable bearing posts or standards 38 upon opposite sides of the tank. The parallel arms 39 of the yoke lever have adjustably secured thereto weights 40. This yoke lever is normally disposed in horizontal position, and the roller 36 bears against 75 the under surface of the tank adjacent the free end thereof to support the said tank. The weights 40 may vary in size, according to the quantity of material which it is desired the tank shall hold before starting to 80 swing downwardly. By adjusting the weights upon the arm ends, it is obvious that the time for swinging movement of the tank may be regulated.

Mounted for longitudinal sliding movement on the arms 39 are weights indicated at 41. These weights carry rollers 42, the uppermost of which support the said weights upon the arms. The upper or supporting surfaces of the arms 39 are inclined downwardly toward their free ends, so that when the yoke lever is in horizontal position, the weights 41 will gravitate to the outer or free ends thereof. Stops 43 are located upon the arms to limit the inward sliding movement 100 of the said weights.

When the tank is emptied, the yoke lever will assume horizontal position, and the weights will hold the tank at the limit of its upward movement. When a quantity of 105 liquid sufficient to overcome the weights has been admitted to the tank, the bight portion of the yoke lever will move downwardly, whereupon the arms 39 will be raised. Immediately, the roller weights 41 will move 110 inwardly from the arm ends, whereupon the leverage is reduced. This action permits of the tank moving at a more rapid rate, and the valve 14 will at once be actuated. When the liquid within the tank has escaped therefrom, the weights will move the tank upwardly to normal position, and the sliding weights 41 will again assume normal position at the outer ends of their supporting arms 39.

In operation, water and oil is fed to the tank through the pipe 11. Any gases which might be conveyed to the tank with the water and oil will escape therefrom through the pipe 12, and it will be understood that the main gas exhaust pipe may be connected with a suitable storage tank for the gas. As the water and oils accumulate in the tank in sufficient quantity to over balance the springs and weights, the free end of the tank 130

will descend, whereupon the valve 14 in the drain will be actuated to permit of the liquids escaping.

It will be observed, from the foregoing, 5 that an extremely simple and yet thoroughly efficient means for attaining the various ends has been provided, and the various movable parts of the mechanism are so arranged as to present little opportunity for derangement, wear or breakage. The adjustment of 10 the yieldable supporting means may be readily made, so as to enable the tank to attain predetermined quantities of water or oils before operating the exhaust or drain mechanism.

While the present is a disclosure of the preferred embodiment of the invention, it is to be understood that the invention is not limited thereto, as various changes may be 20 made in the construction, arrangement, and proportion of parts, without departing from the spirit of the invention as defined in the appended claims.

What is claimed is:—

25 1. In a device of the class described, a tank pivoted at one end and having a drain at its free end, a supply pipe for said tank, means governed by the downward movement of said tank for opening said drain, and a 30 spring supporting the free end of said tank.

2. In a device of the class described, a tank, a pair of pipes communicating with said tank at one end, the outer ends of said pipes projecting in opposite directions and 35 in axial alinement, bearings for said ends, a drain valve at the opposite end of said tank, means for yieldably supporting the free end of said tank, and means governed by the movements of said tank for controlling said 40 valve.

3. In a device of the class described, a tank, the said tank being pivoted at one end

and being capable of swinging vertically, a drain pipe at the free end of said tank, a lift valve in said drain, standards carried 45 by said drain and being arranged one upon each side of said valve, levers pivoted at one end to said standards and extending therefrom in crossed relation past the stem of said valve, the said levers being secured to said stem, the free ends of said levers projecting beyond the said tank, and stops adjacent the free ends of said levers and against which the latter are adapted to engage.

4. The combination with a vertically movable tank, of a post beneath and adjacent one end of said tank, a lever pivoted horizontally on said post and having its upper surface inclined downwardly at one end, a roller 60 on the opposite end of said lever engaged with said tank, a rolling weight on the inclined end of said lever, and a stop on the free end of said inclined extremity.

5. The combination with a vertically movable tank, a valve in said tank adapted to open when the said tank moves a predetermined distance downwardly, a yoke pivoted beneath said tank, the bight portion of said yoke being engaged with the said tank, the 70 upper edges of the arms of said yoke being inclined downwardly at their outer ends, rolling weights on the said arms, stops at the outer ends of said arms to limit the movement of said weights in one direction, 75 and springs tending to lift said tank.

In testimony whereof we affix our signatures in presence of two witnesses.
